UNITED STATES PATENT OFFICE.

RICHARD WADE LLOYD, OF VERNDALE, MINNESOTA.

LIQUID-DISPENSING DEVICE.

1,229,105.

Specification of Letters Patent. Patented June 5, 1917.

Application filed July 6, 1916. Serial No. 107,819.

To all whom it may concern:

Be it known that I, RICHARD W. LLOYD, a citizen of the United States, residing at Verndale, in the county of Wadena and State of Minnesota, have invented certain new and useful Improvements in Liquid-Dispensing Devices; and I do declare the following to be a full, clear, and exact description of the invention, such as will enable others skilled in the art to which it appertains to make and use the same.

My invention relates to improvements in liquid dispensers and more particularly to operating mechanisms for the pumps or other control units thereof.

The object of the invention is to provide a simple and inexpensive arrangement of parts for accurately vending different quantities of liquid upon the insertion of a coin, the device being primarily designed for dispensing gasoline and being operable from coins of different values, the quantity of liquid discharged being controlled by the value of the coin.

With the foregoing general object in view, the invention resides in certain novel features of construction and in unique combinations of parts to be hereinafter fully described and claimed, the descriptive matter being supplemented by the accompanying drawings which constitute a part of this application and in which:

Figure 1 is a front elevation of the improved liquid dispensing device;

Fig. 2 is a sectional view thereof on the plane of the line 2—2 of Fig. 1 with all parts in normal position;

Fig. 3 is an enlarged sectional view similar to Fig. 2, showing the manner in which the machine is set in operation by the insertion of a quarter of a dollar;

Figs. 4 and 5 are transverse sections on the planes of the lines 4—4 and 5—5 of Fig. 3;

Figs. 6, 7 and 8 are detail sectional views showing different positions of parts to be described.

In specifically describing the structure shown in the drawings above briefly described, similar characters will be employed to designate corresponding parts throughout the several views and reference will be herein made to the numerous elements by their respective indices. To this end the numeral 1 designates a hollow standard ris-

ing from a pump cylinder 2 but not in communication therewith, said cylinder and the lower end of the standard being adapted to be embedded in the ground as is also a supply tank (not shown), which tank supplies the liquid to the cylinder 2 through the pipe 3. A check valve 4 is disposed at the lower end of the cylinder 2 to prevent the return of liquid therefrom into the pipe 3, and a piston 5 is mounted in said cylinder, said piston also having a check valve designated at 6, this valve being adapted to open and the other to close when the piston is forced downwardly to its normal position, whereupon liquid will be contained in the cylinder 1 above said piston to be discharged when the latter is raised, a suitable discharge pipe 7 being provided. The pipe 7 leads from the upper end of cylinder 2 to a suitable point above the ground and is equipped with any suitable type of discharge neck 8.

The features of construction so far described are merely shown for illustrative purposes and it is to be understood that the gist of the present invention now to be described is applicable equally as well to other types of liquid dispensers.

An operating member in the form of a vertical rack bar 9 is adjustably secured at 10 to the upper end of the piston rod 11 which rises from the piston 6, the teeth of said bar being in mesh with a pinion 12 driven by an electric motor 13 when the circuit of said motor is completed. A laterally swinging knife switch 14 is disposed approximately parallel to the bar 9 and for illustrative purposes is shown as pivoted at its upper end at the point 15 to a suitable bracket 16, the lower end of the switch 14 co-operating with a contact 17. One lead wire 18 extends to one terminal of the motor 13 while leading from the other terminal thereof and electrically connected in any preferred manner with the knife switch 14, 100 is an additional wire 19. The other lead wire 20 is connected with the contact 17. It will thus be evident that when the switch 14 is closed or in other words moved from the position shown in Fig. 2 to that designated in Fig. 3, the circuit will be completed with the result that the motor 13 will be driven to raise bar 9. This raises piston 6 through the instrumentality of rod 11 and dispenses a quantity of liquid which 110

is controlled by the distance which bar 9 is permitted to move upwardly, said bar having a number of ranges of movement and being limited to any one of said ranges by a plurality of stops to be described.

Slidably mounted in suitable bores 21 which open through the edges of rack bar 9, is a plurality of horizontal stop pins 22 which will be limited in their movement by 10 suitable stops 23 as shown most clearly in Fig. 3. When the bar 9 stands in its normal lowered position, to which position it is always returned by a coiled spring 24, the pins 22 will stand opposite arms 25 which 15 project laterally from the knife switch 14. Disposed opposite the pins 22 when in their normal positions, are studs 26 which are mounted on one end of plungers 27, said plungers being slidably mounted in suitable 20 casings 28, each of which is provided with a coin chute 29 adapted to direct coins of different values into spaces 30 between the inner ends of the plungers 27 and operating slides 31 (see more particularly Fig. 3). The 25 slides 31 are normally projected slightly across the lower ends of the chutes 29 by means of coiled springs 32 whereby to check the downward movement of any coin a sufficient length of time to permit permanent 30 magnets 33 to act on said coin if it be of magnetizable metal. When, however, any slide 31 is retracted manually by means of its respective knob 31' the coin, if not counterfeit, will drop into the space 30, whereupon 35 the slide 31 may be shifted in the opposite direction with the result that its respective plunger 27 will be projected through the instrumentality of the coin until the latter reaches the discharge chute 34, one 40 of these chutes being provided for each casing 28 as shown. Coiled springs 35 are provided for returning the plungers 27 to their normal positions.

When any stud 26 is projected by its respective plunger 27 it will in turn project the adjacent stop pin 22, the latter now forcing against one of the arms 25 to throw the knife switch 14 into engagement with the contact 17. The result is that the motor 45 13 is set in operation and raises bar 9 to discharge liquid through the pipe 7 and nozzle 8. The end of the pin which has been projected is adapted to strike a switch cut-out member when the bar 9 moves upwardly a predetermined amount, whereupon 50 the motor will be brought to a standstill and said bar will be returned to its normal position. During this latter movement, the projected pin will also be returned to its 55 retracted position, all of this taking place due to the arrangement of the novel features of construction explained below.

For illustrative purposes the switch cut-out member is shown in the form of an arm 60 36 projecting rigidly from the pivoted upper

end of the knife switch 14, said arm being disposed in the upward path of the pins 22 when projected. It will thus be clear that as any one of said pins is brought into contact with arm 36, the latter will be forced 70 upwardly to a sufficient extent to throw the switch 14 horizontally and thus disengage it from the contact 17. If the pin be projected, say by the insertion of a dime, the bar 9 will only move upwardly a slight distance and will consequently vend only a small amount of liquid before the aforesaid pin strikes arm 36 and breaks the circuit of motor 13. However, if any of the other pins 22 are projected by the insertion of coins of 80 greater value in their respective casings 28, through the chutes 29 thereof, the bar 9 will move a correspondingly greater distance with the result that more fluid will be discharged from the device.

A normally lowered upwardly moving cam 37 is pivoted within a recess formed in the bracket 16 in such a manner as to permit it to swing upwardly, but to limit its downward movement to a substantially horizontal 90 position. The outer ends of the pins 22 and the cam 37 are beveled in the same direction as shown respectively at 22' and 37'. The cam 37 is disposed beneath the arm 36 so that the active pin 22 will first contact with 95 said cam and tilt it upwardly until it is cleared by said pin. The moment this takes place, the cam again returns to its normal position and at approximately the time this occurs, the projected pin 22 comes in contact with arm 36 and opens the switch 14. This of course cuts off the current of motor 13 with the result that the tension of spring 24 now moves bar 9 downwardly to its normal position. As this movement takes place the bevels 22' and 37' come in contact with the result that the pin 22 which has been projected will be returned to its normal position to be again forced outwardly when its respective stud 26 is actuated.

A suitable casing 39 will be disposed over all working parts and will be supported by the standard 1 if the latter be employed, and within said casing is a coin box 40 in which the coins from the chutes 34 are received, an 115 appropriate door 41 being provided for the purpose of removing the cash when desired.

By constructing the improved vending machine in the manner shown and described it will be highly efficient and durable and 120 will need no operator. As above stated the devices are well adapted for vending gasoline and they may well be placed at intervals along highways, but they may also be used to advantage in garages and the like. 125

From the foregoing, taken in connection with the accompanying drawings, the construction, manner of operation and advantages will be understood but in conclusion I will state that although certain specific de- 130

tails have been shown and described for accomplishing probably the best results, numerous changes may be made within the scope of the invention as claimed without sacrificing the main characteristics thereof.

5 I claim:—

1. An operating mechanism for liquid dispensers, comprising a movable operating member, means for moving the same to permit the discharge of liquid, stop means for limiting the movement of said member to a number of ranges, and coin controlled means for setting the stop means according to the value of the coin inserted and for simultaneously throwing the first-named means into operation automatically. 70
2. An operating mechanism for liquid dispensers, comprising a movable operating member, means for moving the same to permit the discharge of liquid, a plurality of projectable and retractable stops for limiting the movement of said member to a number of ranges, said stops also serving to throw the first-named means into operation when projected, and coin controlled devices for projecting said stops, one of said devices being provided for each stop and said devices being operable from coins of different values. 75
3. An operating mechanism for liquid dispensers, comprising a movable operating member, means for moving the same to permit the discharge of liquid, a plurality of projectable and retractable stops mounted on said member for limiting the movement thereof to a plurality of ranges, said stops also serving to throw the first-named means into operation when projected, and coin controlled devices for projecting said stops, one of said devices being provided for each stop and said devices being operable from coins of different values. 80
4. An operating mechanism for liquid dispensers, comprising a movable operating bar, means for moving the same endwise to permit the discharge of liquid, said bar having a plurality of longitudinally spaced bores opening through its edges, sliding stop pins mounted in said bores and adapted to limit the movement of the bar to a number of ranges, and a plurality of coin controlled devices for projecting said pins, one of said devices being provided for each pin and said devices being operable from coins of different values. 85
5. An operating mechanism for liquid dispensers, comprising a movable member, electric means for moving the same to permit the discharge of liquid, a plurality of projectable and retractable stops for limiting the movement of said member to a number of ranges, any of said stops serving when projected to complete the circuit of the aforesaid electric means and also to break 90 said circuit when the aforesaid member has
6. An operating mechanism for liquid dispensers, comprising an operating member adapted to be moved to permit the discharge of liquid, electric means for so moving said member, an electric switch adjacent said member for completing the circuit of said electric means, a plurality of projectable and retractable stops mounted on said member for limiting the movement thereof to a number of ranges, any of said stops serving when projected to close said switch, and a plurality of coin controlled devices for projecting said stops, one of said devices being provided for each stop and said devices being operable from coins of different values. 95
7. An operating mechanism for liquid dispensers, comprising a movable operating bar to be shifted endwise to permit the discharge of liquid, electric means for so shifting said bar, an electric switch adjacent said bar for completing the circuit of said electric means, said bar having a plurality of bores opening through its edges and spaced longitudinally, sliding stop pins mounted in said bores for limiting the movement of said bar to a number of ranges when projected, any of said pins serving to close the aforesaid switch when so projected, and a plurality of coin controlled devices for projecting said pins, one of said devices being provided for each pin and said devices being operable from coins of different values. 100
8. An operating mechanism for liquid dispensers, comprising a movable operating member, means for moving said member to permit the discharge of liquid, a plurality of longitudinally spaced projectable and retractable stops mounted on said member, to limit the movement thereof to a number of ranges, a plurality of coin controlled devices for projecting said stops, a cam disposed in the upward path of any of the stops when projected, and a cut-out member disposed beyond said cam for throwing the first-named means out of operation when engaged by a projected stop, whereby the operating member is permitted to return to its normal position, the cam being adapted to return the projected stop to its initial position during this movement. 105
9. An operating mechanism for liquid dispensers comprising a movable operating member, means for moving said member, stop means mounted on said member, means for setting the stop means and automatically throwing the moving means into operation at substantially the same time, a control member in the path of the stops for throwing the moving means out of action to permit the operating member to return to its 110
- 125
- 130

initial position, and means for returning the stop means to normal position as said member travels on its return movement.

10. An operating mechanism for liquid dispensers comprising a movable operating member, means for moving said member, a plurality of projectable and retractable stops for limiting the movement of said member to a number of ranges, and coin controlled devices for projecting said stops.

11. An operating mechanism for liquid dispensers comprising a movable operating member, means for moving said member, a plurality of projectable and retractable stops mounted on the operating member for limiting the movement of said member to a number of ranges, and coin controlled devices for projecting said stops.

12. An operating mechanism for liquid dispensers comprising a movable operating member, electric means for moving the same, a switch for completing the circuit of said moving means, and a projectable and retractable member carried by said operating member for closing the switch when projected to permit the moving means to operate said operating member and for opening said switch when said operating member has traveled a predetermined amount.

In testimony whereof I have hereunto set 30 my hand in the presence of two subscribing witnesses.
